UNITED STATES PATENT OFFICE.

CHARLES E. BULLARD, OF BROOKLINE, MASSACHUSETTS, ASSIGNOR OF ONE-HALF TO
GEORGE R. STETSON, OF NEW BEDFORD, MASSACHUSETTS.

ARCH-SUPPORTER.

No. 878,039.

Specification of Letters Patent.

Patented Feb. 4, 1908.

Application filed September 13, 1907. Serial No. 392,669.

To all whom it may concern:

Be it known that I, CHARLES E. BULLARD, a citizen of the United States, residing at Brookline, in the county of Norfolk, State of Massachusetts, have invented a certain new and useful Improvement in Arch-Supporters, of which the following is a specification, reference being had therein to the accompanying drawings.

10 The invention consists in an improved supporter for the arch of the human foot, to be worn inside a boot or shoe.

An arch-supporter embodying the invention comprises a sole-piece to fit loosely within a boot or shoe, and an arch-supporting cushion of elastic material, such as rubber, attached to the shank-portion of the said sole-piece and formed with numerous yielding projections. The said projections, preferably are hollow or cellular, forming a number of small cells to contain air, in order to utilize the elasticity of the contained air, and preferably, also, are formed with holes for ingress and egress of air so that when the 25 arch-cushion is subjected to the pressure of the arch of the wearer's foot in walking, more or less of the said air is expelled from within the cavities of the projections. Through the escape of the air the yielding of the projections is facilitated. The holes are made of a size to properly control the rate of outflow and inflow of the air. The compression of the hollow projections and resulting expulsion of the contained air, and subsequent expansion and inflow of air into the same, occasion a forced circulation of air within the shoe. The sole piece may be composed of any suitable material, leather, for instance, but I prefer to form the same in whole or in 30 part of cork or cork composition in sheet form.

The invention is illustrated in the drawings, in which—

Figure 1 is a sectional view of portion of a 45 shoe and an embodiment of the invention applied thereto. Fig. 2 is a plan of the arch-supporter of Fig. 1, shown separately. Fig. 3 is a view of the arch-supporter of Figs. 1 and 2 in longitudinal section in a plane passing through one of the longitudinal lines of hollow projections. Fig. 4 is a plan of an arch-supporter having the sole-piece composed in part of two or more layers. Fig. 5 is a view in longitudinal section of the arch-

supporter, of Fig. 4, showing a layer of cork or cork composition.

Having reference to the drawings,—at 1, Fig. 1, is shown a portion of the upper of a boot or shoe, at 2 a portion of the outer sole, and at 3 a portion of the inner sole thereof. 60

At 4, Figs. 1, 2 and 3, is shown the layer of flexible material constituting the sole-piece of the improved arch-supporter, and at 5 is the elastic arch-cushion. The sole-piece is shaped to conform to the waist-portion or 65 shank of a boot or shoe, and to fit within the heel-portion thereof and also enter partially within the fore-part. The arch-cushion 5 is applied to the shank-portion of the sole-piece, the heel-portion of which projects at 70 the rear of the said cushion while the front end-portion of the sole-piece also projects at the front end of the cushion, as clearly shown. The arch-cushion usually will be cemented to the under side of the sole-piece. 75 When the arch-supporter is in place within a boot or shoe, the arch-cushion overlies the shank of the latter, while the rearward extension of the sole-piece 4 beyond the arch-cushion rests upon the inner sole 3 in the heel-portion of the boot or shoe, and the forward extension beyond the arch-cushion rests upon the said inner sole in the fore-part of the boot or shoe. The said forward extension is tapered or skived off, as shown, in order 80 that there may be no abrupt shoulder or 85 prominence at its front edge when the arch-supporter is in place in a boot or shoe.

The projections of the arch-cushion are designated 6, 6, etc. The shape of the same 90 may vary, as deemed advisable. In this instance they are formed as portions of spheres, and hollow, to contain air, as stated above, with the holes 7, 7, etc., constituting passages for ingress and egress of air. The said 95 projections are of graduated size, being most prominent at the middle of the length of the air-cushion and progressively less prominent toward the front and rear ends of the cushion in order that when the arch-supporter is in 100 place in a boot or shoe the arch-cushion may support the shank-portion of the sole-piece in the form of a gradually rounded arch.

Figs. 1 and 3 show the sole-piece composed of a single layer. Figs. 4 and 5 show 105 the same composed of two layers, united together, the under or main layer 4^a being made of cork or cork-composition, and the upper

layer 4^b being a facing layer of thin leather or cloth.

After being worn for a short time, an arch-supporter constructed in conformity with my invention, becomes molded by the pressure of the foot of the wearer so as to assume the transverse curvature of the shank and waist of the shoe in which it is used, and so as to fit closely to the arch of the foot and against the hollow of the inner side of the said arch. It assumes also a concave shape at the rear of the arch-cushion, conforming to the under portion of the ball of the heel.

While contrived to afford adequate support to the arch of the foot of the wearer, my improved arch-supporter is sufficiently yielding to obviate inconvenience and discomfort to the wearer.

What is claimed as the invention is:—

20 1. The improved arch-supporter comprising the sole-piece of flexible material shaped to fit within the heel-portion, waist, and fore-part of a boot or shoe, and having at the intermediate or shank-portion thereof yielding projections forming a cushion to occupy and support the arch of the wearer's foot.

25 2. The improved arch-supporter comprising the sole-piece of flexible material shaped to fit within the heel portion and waist of a boot or shoe, and having at the shank-portion thereof numerous prominent portions

containing small air-cells and forming a cushion to occupy and support the arch of the wearer's foot.

3. The improved arch-supporter comprising the sole-piece of flexible material shaped to fit within the heel-portion and waist of a boot or shoe, and having the shank-portion thereof provided with an arch-cushion formed with numerous small hollow yielding 40 projections

4. The improved arch-supporter having the body-portion thereof shaped to fit within the heel-portion and waist of a boot or shoe, and having hollow yielding projections decreasing in height from middle of shank-portion toward front and rear, respectively, forming a graduated arch-cushion.

5. The improved arch-supporter having the body-portion thereof shaped to fit within 50 the heel-portion and waist of a boot or shoe, and having a yielding cushion containing numerous small air-cells and graduated in height from middle toward front and rear, respectively, to occupy and support the arch 55 of the wearer's foot.

In testimony whereof I affix my signature in presence of two witnesses.

CHARLES E. BULLARD.
